JOSEPH C. FIELD, OF ORANGE, NEW JERSEY, ASSIGNOR TO WESTERN ELECTRIC COMPANY, OF NEW YORK, N. Y., A CORPORATION OF ILLINOIS.

SELECTIVE SIGNALING SYSTEM.

1,127,876.

Specification of Letters Patent.

Patented Feb. 9, 1915.

Application filed August 23, 1912. Serial No. 716,643.

To all whom it may concern:

Be it known that I, JOSEPH C. FIELD, a citizen of the United States, residing at Orange, in the county of Essex and State 5 of New Jersey, have invented a certain new and useful Improvement in Selective Signaling Systems, of which the following is a full, clear, concise, and exact description.

This invention relates to selective signaling systems of the class in which a plurality of waystations located upon a line are each provided with selective circuit closing devices for operating a local signal and more particularly to a system in which a plurality of these lines emanating from a central or common station are arranged for intercalling or intercommunicating.

The object of the invention is in general to provide new and improved means in a 20 system of this class whereby all of the lines emanating from a common station may be operated from a common source of current without interference between the various circuits.

25 In accordance with this invention there is provided in each of the lines an impulse relay which is operable by means of a circuit including the line wires and the central source and is adapted when operated 30 to connect the said common source with the line wires for operating the selectors. The impulse relay being constantly in the battery circuit must differentiate between the selector operating current and the current 35 to which it responds and this is accomplished by providing this relay with windings which act differentially to current through them in series, but aid when in multiple.

40 The drawing is a diagram of the apparatus and connections of a system embodying this invention.

In the drawing there are shown two pairs of line wires 5, 6 and 5, 6 each having a 45 sending station A, and two waystations B and C connected therewith. The equipment at each of these waystations is the same and comprises slow and quick acting magnets 9 and 10 designated as holding 50 and stepping magnets, and holding and stepping pawls 11 and 12 controlled by said magnets 9 and 10 to advance a ratchet wheel 13. The ratchet wheel operates in its advancement to close contact 14 to complete 55 the circuit of a local signal 15 at the way-

station. The holding and stepping magnets are connected in series with each other and in bridge of the line wires 5 and 6. Included in the bridge with the holding and stepping magnets are retardation coils 16 and 17 and a variable resistance 18, the retardation coils being for the purpose of protecting the selector against lightning discharges and the variable resistance being provided for tapering the line resistance. 60 Also located at each of the waystations is an impulse transmitting device 20 controlling two contacts 21 and 22 which when closed in the operation of the transmitter connect ground with the line conductors 5 and 6 through windings 25 and 26 of a coil 70 and the retardation coils 16 and 17.

The operating current for the selectors of each pair of line wires is furnished by a source of current 30 located at the sending 75 station and having one pole grounded at 31. Associated with each of the lines at the sending station is an impulse relay 32 each having two windings 33 and 34. The winding 33 of each of the relays has one terminal 80 connected directly with the line wire 5 and the other connected with the non-grounded pole of the source of current 30 through conductors 35 and 36. One terminal of the winding 34 of the relay 32 is connected with 85 the line wire 6 while the other terminal thereof is normally connected with the non-grounded pole of the source of current 30 through a normally closed contact 37 controlled by the relay and a resistance 38. 90 The operation of the relay 32 will close a contact 40 and open the contact 37 disconnecting the winding 34 from the non-grounded pole of the source of current 30 and connecting it with the opposite pole 95 thereof, the purpose of which will be more clearly set forth in the description of the operation of the system. The windings 33 and 34 of the relay 32 are differentially related with respect to current passing 100 through the line wires in series but aiding with respect to current over the two line wires in parallel.

Referring now to the operation of the system it will be assumed that the attendant 105 at station B on one of the lines desires to signal the station C or any other station on the same line. In order to do this he will operate his impulse transmitter 20 which has on it notches corresponding in number 110

with the number of current impulses required to close the signaling contact of the selector at the desired station.

The impulse wheel 20 carries an arm 68 having its free end insulated and bearing upon a spring 66 in the normal position of the wheel 20 to maintain the contact 22 open. As soon however as the wheel 20 starts to rotate, this arm 68 becomes disengaged from the spring 66 and permits it to close contact 22 and maintain it closed until the wheel 20 completes its revolution. An arm 67, engaged by teeth on the wheel 20, intermittently closes contact 21 in the rotation of the wheel 20, in accordance with the arrangement of the teeth on the periphery of said wheel.

The contacts 21 and 22 are bridged together so that as the contact 21 is made and broken ground will be intermittently connected with the two line wires and an energizing circuit will be completed for the impulse relay 32 which circuits may be traced as follows: One will be from ground 20 through contact 21, winding 25, retardation coil 17, line conductor 5, winding 33 of relay 32 and conductors 35 and 36 to the battery 30; the other being from ground through the contact 21, contact 22, winding 26, retardation coil 16, line conductor 6, winding 34 of relay 32, contact 37, resistance 38 and conductors 35 and 36 to the source of current 30. Current through either or both of these circuits just traced will energize the relay 32 which will operate to close the contact 40 and open the contact 37. The opening of the contact 37 will interrupt the energizing circuit of the winding 34, and complete an energizing circuit for the selector 25 which may be traced as follows: from the non-grounded pole of the source of energy 30, over conductors 36 and 35, the winding 33 of the relay 32, line conductor 5, retardation coil 17, stepping and holding magnets 40 10 and 9 of the selector, variable resistance 18, retardation coil 16, line conductor 6, winding 34 of the relay 32, contact 40 of said relay, conductors 50, 51 and 52 to the grounded pole of the source of current 30. This path includes the two windings 33 and 50 55 34 in series so that the relay 32 will be connected differentially and will not remain energized after the contact 21 is opened. The arrangement whereby the energizing circuit 55 through one winding of the relay 32 is broken after the operation of the relay is of importance in a scheme of this sort as it means that any leaks to ground which might have the effect of preventing the release of 60 the relay when operated from any one of the waystations, are practically halved in value after it operates, and said relay can therefore be released through practically twice the amount of leak that it would be possible 65 to release it through if it is receiving cur-

rent over both sides of the line. In other words the operation of the relay 32, by opening one of the parallel paths over which it is normally energized, increases the resistance of the path for current through it to approximately twice the value over which it was originally energized, so that the current flowing through the relay before opening the remaining path is only about one-half of the original energizing current.

Connected in the line wires 5 and 6 at the sending station are retardation coils 60 and 61 acting in conjunction with a condenser 62 bridged across said line wires to smooth out or graduate the current impulses used in selecting so that no disagreeable click or thump will be heard in receivers which may be connected with the line wires during a signaling operation.

The resistance 38 is non-inductive and serves as a temporary discharge path for the retardation coils 60 and 61 and the condenser 62 in order that the current impulses on a heavily loaded line will not be too prolonged to permit the proper operation of the stepping magnet.

The impulse relay 32 may be operated from the sending station by means of a transmitting device 65 which when operated completes a circuit through the winding 33 of said relay from the battery 30 which may be traced from the grounded side of said battery, over conductor 52, conductor 51, the contact controlled by 65, winding 33 and conductor 36 to the non-grounded pole of the battery 30. Current over this circuit energizes the relay 32, causing it to close the contact 40 to connect battery with the line wires 5 and 6 to operate the selectors.

The scheme described provides for the operation of a number of separate circuits from a single source of current thus avoiding the use of a number of separate sources requiring a large number of cells the installation and maintenance of which is a material item of expense.

What I claim is:—

1. In a selective signaling system the combination with line wires having a sending station and a plurality of waystations connected therewith, of a selector in bridge of said line wires at each of said waystations responsive to current impulses, a source of current at said sending station, an impulse relay at said sending station connected with said source of current and said selectors for intermittently connecting said source of current with the line wires, said relay having means for rendering it non-responsive to said selector operating current, and apparatus and connections at said waystations and said sending station for completing an operating circuit for said relay including said source of current.

2. In a selective signaling system the com-

bination with line wires having a sending station and a plurality of waystations connected therewith, of a selector in bridge of said line wires at each of said waystations responsive to current impulses over the line wires in series, a source of current at the sending station, electromagnetic means connected with said source and said selectors for impressing selector operating currents upon the line wires, said electromagnetic means having means for rendering it non-responsive to said selector currents, and apparatus and connections at said sending and waystations for completing an operating circuit for said electromagnetic means.

3. In a selective signaling system the combination with line wires having a sending station and a plurality of waystations connected therewith, of a selector in bridge of said line wires at each of said waystations responsive to current impulses, a source of current, an impulse relay connected in said line wires between said source of current and said selectors for intermittently connecting said source of current with the line wires, said relay being provided with two windings effective when in multiple but ineffective when in series, and means at each of said waystations for connecting said windings in multiple.

4. In a selective signaling system the combination with line wires having a sending station and a plurality of waystations connected therewith, of a selector in bridge of said line wires at each of said waystations responsive to current impulses over the two line wires in series, a source of current, an impulse relay having two windings connected in said line wires between said source of current and said selectors, said windings being differentially related when in series and aiding when in multiple, means controlled at each of said waystations for connecting said windings in multiple and means con-

trolled by said relay in its operation for connecting said windings in series.

5. In a selective signaling system the combination with line wires having a sending station and a plurality of waystations connected therewith, of a selector in bridge of said line wires at each of said waystations responsive to current impulses, a source of current, an impulse relay having two windings in said line wires between said source of current and said selectors, said windings being differentially related when in series and aiding when in multiple, means at each of said waystations for connecting said windings in multiple, means controlled by said relay in its operation for connecting said windings in series, and means also controlled by said relay in its operation for opening the energizing circuit through one of said windings.

6. In a selective signaling system the combination with a plurality of pairs of line wires emanating from a common station and having a plurality of waystations connected therewith, a selector in bridge of each pair of line wires at each of said stations responsive to current impulses, a single source of current located at a central station for operating said selectors, an impulse relay for each pair of line wires located at said common station, and operable by current from said source; and means at each of said way stations for grounding the two line wires to complete an operating circuit for the relay of its particular line independently of the other relays of the other lines.

In witness whereof, I hereunto subscribe my name this 22nd day of August A. D., 1912.
